[57] ABSTRACT

A mechanized carbon reaming apparatus for pipes utilizes a low speed, high torque drive means, interchangeably receives standard manual type pipe reamers, mechanically removes "caked" carbon collected on the inner wall or "bowl" of briar pipes and the like and collects the scrapings in a cup-tray.

MECHANIZED REAMING APPARATUS FOR PIPES

BACKGROUND OF THE INVENTION

1. Field of the Invention

This device relates to apparatus for removal of carbon from the bowl of pipes and particularly to mechanically driven pipe reamers.

2. Description of the Prior Art

When smoking pipes, repeated burning of tobacco causes carbon to build up on the walls of the pipe bowl. When approximately one-sixteenth inch of carbon or cake builds up on the inner wall of the pipe bowl, the carbon cake should be removed to prevent cracking of the bowl and to provide more space for tobacco in the pipe bowl. Removal of collected carbon from the bowl of briar pipes has long been done manually with hand tools such as files, knife blades, scrapers and commercially available hand carbon-cut reamers. Pipe smokers desire some carbon cake on the inner wall of their pipes but a cake of more than one-sixteenth inch is not desirable. When removing the carbon cake from the pipe bowl, it is important not to use an instrument with a sharp point otherwise damage to the pipe may occur. A pipe reamer or carbon-cutter made to the shape of the pipe bowl is recommended for removing the carbon cake. Careful handling of the reamer or carbon-cutter is necessary otherwise "wounding" of the briar in the pipe may occur if the carbon cake is not properly removed. Ordinary hand reaming of the bowl cake often is unsatisfactory because of lack of uniformity in removal of the cake.

In addition to hand reamers, various types of mechanical reamers and apparatus have been developed and patented. Reference is made to U.S. Pat. Nos. 3,438,380; 3,362,416; 2,252,175; 2,306,622; 2,189,942; 1,651,651; and 1,233,410 which give a background of existing reamer types.

Several of these patents employ mechanically driven cleaning or reaming devices. However, heretofore most of the commercially available, mechanically driven reamers have been driven at such high speed that dust and scrapings have been scattered in the surrounding area. In order to overcome this undesirable condition, many of the mentioned devices have necessarily provided for the cleaning or reaming operation area to be enclosed with various housings or bellows arrangements. Also, many of the pipe cleaning or reaming devices have had to employ suction fans to remove and control the removal of the dust and scrapings from the reamer and pipe bowl area.

The prior art devices normally require, for mechanized reaming, a special reamer which is useful only with the driven apparatus and has no utility as a manual reamer. Thus, it would be desirable to provide a mechanized pipe bowl reamer on which a conventional type manual reamer could be removably mounted so that the same reamer could be either mechanically driven or used manually for final touch up reaming.

Another problem faced by pipe smokers is that bowls of different depth require different depth reamers. While the problem has been recognized in some of the mechanized bowl reamers of the prior art it has not been satisfactorily solved. More particularly, the prior art has not provided a mechanized pipe bowl reamer adapted to removably mount various sizes of manual reamers for various depths of bowls.

With the addition of the housings, bellows, fans, etc., a relatively large and expensive device exists. In this respect, the prior art has not taught an adequate, inexpensive, mechanically driven device for reaming of the carbon cake from a pipe bowl.

SUMMARY OF THE INVENTION

This invention relates to a mechanized pipe reamer which adapts to pipes having various bowl depths and 10 which utilizes a drive means enclosed within a housing such that its drive shaft extends through the top of the housing and slidably receives a removable cup-tray. The exposed end of the drive shaft integrally mounts a 15 shaft extension which interchangeably receives various sizes of manual type flanged carbon-cut reamers and mounts the selected reamer at either of two levels. In utilizing the mechanized pipe carbon reaming apparatus, a pipe bowl is turned upside down over the flanged carbon-cut reamer so that the pipe bowl and reamer 20 are contacting each other. The drive means is energized for turning of the reamer and adequate pressure of the pipe is applied to the turning reamer for removal of the carbon. As the carbon is reamed from the bowl of the pipe, the removed carbon falls by gravity into the 25 tray below the reamer. The tray may be removed and periodically emptied.

DESCRIPTION OF THE DRAWINGS

FIG. 1 is a side elevation view of the mechanized 30 reaming apparatus for pipes with a portion thereof cut-away and illustrating in section a pipe of relatively shallow bowl depth being reamed of its carbon cake.

FIG. 2 is a front elevation view of the apparatus of 35 FIG. 1 but showing in section a pipe of relatively deep bowl depth.

FIG. 3 is a top plan view of the apparatus as it appears with the cup-tray removed from the apparatus.

FIG. 4 is a side elevation view of the extension shaft employed with this invention and with the shaft turned so that the uppermost reamer mounting slot is visible.

FIG. 5 is a view similar to that of FIG. 4 but with the shaft turned so that the lowest reamer mounting position is shown.

FIG. 6 is a top view of the shaft of FIGS. 4 and 5.

FIG. 7 is a partial section view, enlarged, of the cup-tray employed with this invention.

FIG. 8 is a side elevation view, on a reduced scale, of a manual flanged carbon-cut reamer of the type used in this invention.

DESCRIPTION OF THE PREFERRED EMBODIMENT

Referring now to the drawings, the mechanized reamer 10 has a housing 11 which fixedly mounts a low-speed, high-torque drive motor 12. Bolts 13 extend through the top of housing 11 and into motor 12 so that, when tightened, motor 12 is fixedly secured to housing top 14. A metal plate 15 closes the bottom end of housing 11 and is secured thereto by screws 22. Suction cups 16 aid in preventing the unit from sliding on the surface upon which it is resting. A power cord 17 extends from motor 12 through opening 18 in housing 11 and has a plug 19 for insertion into a suitable outlet. On/off switch 20 is mounted on an angled surface 21 of the front housing 11.

A motor found suitable for purposes of the invention is made by E. C. M. Motor Company of Schaumburg,

Illinois and is identified as A. C., type SDM1, 25 r.p.m., direct drive. In operation, it provides the desired relatively high torque and low speed which has been most effective for the reaming operation.

Housing top 14 has a square recessed area 23 cut therein. In the center of recessed area 23 is a hole 25 which extends through housing top 14. Drive shaft 26 of motor 12 extends upward through hole 25. A drive shaft extension 27 is secured on shaft 26 by set screw 28 through threaded opening 24 in extension 27 so that as motor 12 drives shaft 26 it in turn causes extension 27 to rotate therewith. The upper exposed end of extension 27 is of hollow construction and has slots 29, 30, 31, 32, which extend down the length of extension 27 a predetermined length. Slot 29 is diametrically opposite slot 30 and slots 29, 30 extend down extension 27 a predetermined portion of its length. Slot 31 is diametrically opposite slot 32 and slots 31, 32 extend down extension 27 a predetermined portion of its length but less than the depth of slots 29, 30. The function of slots 29, 30, 31 and 32 will be described in greater detail later in the description.

Referring to FIG. 7 in detail, a one piece construction cup-tray 40 is square in outside dimensions but has a circular recess area 41 in the middle thereof. Ash receptacle or tray 40 has a downwardly extending extension 42 which is square in construction and which is adapted for placement in square recess 23. The mating of cup-tray extension 42 and recess 23 acts to prevent tray 40 from rotating with shaft 26 and extension 27 when they are being driven by motor 12. Tray 40 has a raised portion 43 molded integral therewith in the center of tray 40. A hole 44 extends through tray extension 42, through tray 40 and through raised portion 43 of tray 40. Hole 44 is of a diameter such that drive shaft extension 27 will be slidably received thereby. As tray 40 is placed on extension 27 it is rotated so that tray extension 42 aligns with square recess 23 in housing top 14, to prevent rotation.

FIG. 8 illustrates a flanged carbon-cut manual reamer 50 of the type which fits all pipes and is employed with this invention. These are conventional hand type reamers 50 which are available in various sizes through tobacco shops. Reamer 50 is comprised of a cutter head 51 which has multiple cutting edges, an integral neck portion 52 and a handle portion 53 which when used manually provides for easier grip and use. As previously stated, the upper exposed end of drive shaft extension 27 is of hollow construction and has slots 29, 30, 31, 32. The hollow, bored, portion of extension 27 is sufficiently large so as to allow the neck portion 52 of reamer 50 to reside therein. Reamer 50 is placed on shaft extension 27 so that handle portion 53 can be aligned and inserted into either of diametrically opposed slot pair 29, 30 or pair 31, 32. Slots 29, 30 are positioned to be used when the pipe being reamed has a shallow bowl (See FIG. 1). Slots 31, 32 are used for a pipe bowl which is relatively deep (See FIG. 2). Once handle portion 53 of reamer 50 is inserted into the desired slot pair and is allowed to seat in its position against the base of the slots, mechanized reamer 10 is ready for use. Handle portion 53 and neck portion 52 are both loosely mounted.

In utilizing the mechanized pipe carbon cutting apparatus, the cup-tray 40 is placed on extension 27 and allowed to seat in square recess 23. Depending on the bowl size of the pipe to be cleaned, a carbon-cut

reamer 50 is selected and mounted on extension 27, as previously described. The pipe to be cleaned is then turned upside down so that the pipe bowl can be placed down over the carbon-cut reamer 50. Switch 20 is now turned on and energizes motor 12. The amount of pressure necessary to provide the desired cut can be applied directly to the pipe as it is being reamed. As the carbon is cut from the inside wall of the pipe bowl, the cut carbon falls into the cup-tray 40 below the reamer.

10 Visual checking of the walls of the pipe until the proper amount of reaming is done gives a simple mechanized apparatus for removing excess carbon cake. When desired, the particular hand reamer so being used may be removed from the reaming apparatus of the invention and employed manually to finish the final reaming.

15 While not illustrated, several modifications or alternatives could be employed with this invention without changing the scope of the invention. It is anticipated that instead of requiring a power cord and power outlet that the apparatus might be battery powered. Another alternative is to utilize a pressure sensitive switch which would cut the motor on when pressure is applied to the pipe as it is held against the reamer. It is also contemplated to provide tobacco storage, pipe storage and reamer storage space in combination with the apparatus of this invention.

20 Of particular advantage is the fact that the shank or neck portion of a conventional manual reamer can be loosely received in the bore of the driven member and the crossbar handle of the reamer loosely received in one of the slot pairs. Thus, reamers may be quickly changed.

25 What is claimed is:

1. A pipe bowl cleaner comprising, in combination:
  - a. a housing including top, side and bottom walls;
  - b. an ash receptacle having a bottom wall portion adapted to be removably secured to said housing top wall in a nonrotatable manner and having a central aperture therein;
  - c. an electric drive motor mounted in said housing;
  - d. a vertical shaft member connected to be driven by said motor and extending through and above said aperture, said shaft member at its upper end having a hollow cylindrical bore and two pairs of slots, each slot in each pair being in opposed relation and of a common selected depth, with one slot pair being at one depth related to reaming shallow bowl pipes and the other pair being at another depth related to reaming deep bowl pipes; and
  - e. a reamer of the type having a flanged reamer at one end, a cylindrical shank and a crossbar handle extending through the shank at the opposite end, said reamer being adapted to bring received and driven by said shaft member with said crossbar loosely residing in a selected slot pair according to the depth bowl to be reamed and with said shank loosely residing in said bore.

50 2. A cleaner as claimed in claim 1, wherein said receptacle is formed with four outer side walls, said housing is formed with four side walls and said receptacle side walls blend with and effectively continue said housing side walls when said receptacle is so secured.

3. A cleaner as claimed in claim 2 wherein said housing top wall includes a noncircular recess and said receptacle bottom wall portion is formed with a mating noncircular formation to reside in said recess and secure said receptacle in said non-rotatable manner.
